(57) **CLAIM**

The ornamental design for an electronic device display with graphical user interface, as shown and described.

DESCRIPTION

FIG. 1 is a front view of an electronic device display with graphical user interface incorporating the design; FIG. 2 is a front view of a second embodiment thereof; FIG. 3 is a front view of a third embodiment thereof; FIG. 4 is a front view of a fourth embodiment thereof; FIG. 5 is a front view of a fifth embodiment thereof; FIG. 6 is a front view of a sixth embodiment thereof; FIG. 7 is a front view of a seventh embodiment thereof; FIG. 8 is a front view of an eighth embodiment thereof; FIG. 9 is a front view of a ninth embodiment thereof; FIG. 10 is a front view of a tenth embodiment thereof; and, FIG. 11 is a front view of an eleventh embodiment thereof. The outermost broken lines in FIGS. 7-11 illustrate an electronic device, the broken line at the periphery of the graphical user interface illustrates the display screen, and the remaining broken lines illustrate portions of the graphical user interface. None of the broken lines form part of the claimed design.
